METHOD FOR POSITIVELY REMOVING A RESISTANCE ELEMENT FROM A WAVEGUIDE

Clarence E. Lasho, Jr., Marion, Iowa, assignor to Collins Radio Company, Cedar Rapids, Iowa, a corporation of Iowa

Application November 5, 1956, Serial No. 620,558

2 Claims. (Cl. 333—98)

This invention relates to waveguides and more particularly to the automatic changing of the frequency of a particular waveguide.

It is well-known that the wave length of a microwave may be changed as it passes through a waveguide. This phenomenon occurs because the wave length depends both upon the frequency of the electrical energy and the physical dimensions of the waveguide. One well-known method of changing the frequency of a waveguide is to introduce a resistance strip or fin into a slot in the waveguide. A resistance strip pressed into a waveguide causes the velocity of transmission along the waveguide to vary, which in turn causes the frequency to change. This fin must be accurately positioned to correctly change the wave length of the microwave signal. If the frequency of the microwave is to be changed by the removal of such a fin, it must be done quickly and positively. This invention is a device which will positively and quickly change the wave length of a waveguide by removing a resistance fin from a slot in the waveguide.

It is an object of this invention to provide a quick and positive method of removing a resistance strip or fin in a waveguide to change the frequency of the waveguide. It is another object of this invention to provide for the automatic removal of a resistance strip or fin from a waveguide to change the frequency of the microwave signal associated with the waveguide. It is still another object of this invention to provide an automatic means for positively and accurately removing a resistance fin from a waveguide where such automatic means is remotely controllable.

These and other objects of this invention will become apparent when the following description is read in conjunction with the drawing in which,

Figure 1 is a perspective representation of one embodiment of this invention; and

Figure 2 is a detailed representation of one fuse usable in this invention.

Referring now to Figure 1, a rectangular hollow waveguide 6 is shown with a slot 7 cut therein. This is a longitudinal slot cut along the center line of one broad side of the rectangular waveguide 6. This slot is normally occupied by the resistance strip or fin 8. Fin 8 is held in position in the waveguide by the slot 7 and the springs 9. Springs 9 hold the fin 8 in the slot by applying spring pressure to the structural member 11. These springs are connected at one end to the structural member 11 through the holes 12. Supporting the other end of the springs is a box-like member 13 and an arm 24 attached thereto. The box-like element or member 13 is removably connected to a supporting unit on the waveguide. This supporting unit includes the arm 14 and necessary structural members to affix the arm to the waveguide. The box-like member 13 is removably connected to the supporting arm 14 by the arm 15 and the screws 18. Due to the perspective nature of the drawing, only one of the springs and the arms are shown in the drawing.

2

It is obvious that any suitable support mechanism may be employed to hold the box-like member to the waveguide.

The normal position of the fin 8 is in the slot 7 of the waveguide 6. It is held in this position by the structure set forth above; however, it may be desirable to instantaneously change the frequency of the waveguide to a specific and definite frequency. It may also be desirable to be able to accomplish this change by remote control means. To accomplish by remote control this change in frequency, the fin 8 is removed in this invention by a novel means. The novel removal system for the fin 8 includes a forceable ejection system. The forceable ejection system of this invention is based upon a fuse 16 which, when activated, generates a force suitable to overcome the spring pressure applied to the member 11. One force which may be used in this invention is the proximity-type fuse similar to the well-known VT fuses used in projectiles. The fuses 16, there being two in the embodiment of this invention for ensuring firing since one fuse is designed with sufficient expansion or force to overcome the spring pressure, are shown in normally contracted condition in Figure 2. Here is illustrated the spiral cuts which are formed into bellows a portion of the length of the fuse 16. One end of the fuse is a flat surface 17 and the other end of the fuse includes two connecting wires 19 which carry the necessary signals to operate the fuse. The wires 19 are connected to the signal source through the connection means 23 which are mounted on an insulating member 20. The fuses which are to be used in this invention do not operate upon an excessive current as the normal fuse operates. This fuse operates upon a predetermined signal of some type. This signal may be either value controlled or 35 possess other distinguishing features. The control signal applied to the wires 19 ignites a small powder charge in the fuse 16 which forcefully extends the bellows 16.

Another bellows 16 extended as shown in Figure 1. The flat surface 17 of the fuse 16 impresses the force resulting from the explosion of the powder and the expansion of the bellows upon the plates 21. These plates 21 are firmly affixed to the structural element 11 and the force resulting from the expansion of the fuses moves the structural member 11 and the connected fin 8 against the pressure of the springs 9. The removal of the element of the member 11 quickly and positively removes the fin 8 from the slot of the waveguide 6 thereby changing the transmission frequency of the waveguide. The fuse 16 require enormous pressures to reform the bellows and must be removed to permit the springs 9 to return the fin 8 to the slot. The frequency change may be accomplished by exploding the fuses by signals from the signal source 22 thereby providing remote control.

Although this invention has been described with respect to a particular embodiment thereof, it is not to be so limited as changes and modifications may be made therein which are within the full intended scope of the invention as defined by the appended claims.

What is claimed is:

1. A system for removing a resistance element from a waveguide including a waveguide having a substantially rectangular cross section, a slot cut in one face of the waveguide and supporting mechanisms on the opposite side of the waveguide from the slot, a resistance element generally conforming to the shape of the slot, means supported on said supporting means for retaining said resistance element in said slot, and means including a positive acting explosive fuse in the shape of a collapsible bellows contained in said supported element for positively removing said resistance element from said slot whereby the frequency of said waveguide is changed.

2. A system for removing a resistance element from a waveguide including a waveguide having substantially rectangular cross section, a slot cut in one face of the waveguide, supporting mechanisms on the opposite side of the waveguide from the slot, a resistance element conforming to the shape of the slot, means supported by said supporting means for retaining said resistance element in said slot, and means including a positive acting fuse in the shape of a collapsible bellows in said supported ele-

ment, said fuse including powder charge activated by an electrical signal for removing said resistance element from said waveguide against the force of said retaining means.
